(57) **ABSTRACT**
The *Cannabis* cultivar 'AFZ' can be briefly characterized by having large purple, green and blue streaked flower clusters that appear almost white due to an immense amount of glandular trichomes that cover every cubic inch of the flower that smells of fresh baked apple pie, diesel fuel, lemon pepper and rubber cement. This hybrid is a very easy to grow and hardy plant that is resistant to most bugs and powdery mildew while able to yield 540-750 grams/m² in a sea-of-green or dense canopy style grow.

3 Drawing Sheets

1

Latin name of the genus and species: *Cannabis sativa*.
Variety denomination: 'AFZ'.

BACKGROUND OF THE NEW PLANT

The present invention relates to a new and distinct *Cannabis* cultivar designated 'AFZ'. This new cultivar is the result of controlled—crosses between proprietary cultivars made by the inventor. AFZ was asexually produced in Orange, CA via stem cuttings and cloning method by the inventor. Asexual clones have been grown and tested indoors and in greenhouses and the properties are found to be transmissible by such asexual reproduction. The cultivar and its traits are stable through many generations of asexual propagation.

TAXONOMY AND NOMENCLATURE

Cannabis, more commonly known as marijuana, is a genus of flowering plants that includes at least three species, *Cannabis sativa*, *Cannabis indica*, and *Cannabis ruderalis* as determined by plant phenotypes and secondary metabolite profiles. In practice however, *Cannabis* nomenclature is often used incorrectly or interchangeably. *Cannabis* literature can be found referring to all *Cannabis* varieties as "sativas" or all cannabinoid producing plants as "indicas". Indeed, the promiscuous crosses of indoor *Cannabis* breeding programs have made it difficult to distinguish varieties,

2

with most *Cannabis* being sold in the United States having features of both *sativa* and *indica* species.

Human cultivation history of *Cannabis* dates back 8000 years (Schultes, R E., 1970, Random thoughts and queries on the botany of *Cannabis*. Pages 11-38 in: C R B Joyce, and S H Curry eds., THE BOTANY AND CHEMISTRY OF CANNABIS. J. & A. Churchill. London, England). Hemp cloth recovered in Europe dates back 6000 years (Small, E, Beckstead, H D, and Chan, A, 1975, The evolution of cannabinoid phenotypes in *Cannabis*, ECONOMIC BOTANY 29(3):219-232). The written record of the pharmacologic properties of *Cannabis* goes back more than 4000 years (Ti, H. 2737 BC. NEI JING SU WEN HUANG TI, Yellow Emperor's Classic on Internal Medicine; referred to 10 15 without citation in Small et al. 1975 Supra).

The taxonomy and nomenclature of the highly variable genus *Cannabis* (Emoden, W A, 1974, ECONOMIC BOTANY 28(3):304-310; Small, E and Cronquist, A, 1976, TAXON 25(4):405-435; Small E and Cronquist, A, 1977, TAXON 26(1):110; Hillig, K W and Mahlberg, P G, 2004, American Journal of Botany 91(6):966-975), remains in question. This is in spite of the fact that its formal scientific name, *Cannabis sativa* L., assigned by Carolus Linnaeus (Linnaeus, C, 1753, SPECIES PLANTARUM, 2:1027, Salvius, Stockholm, Facsimile edition, 1957-1959, Ray Society, London, U.K.), is one of the oldest established names in botanical history and is still accepted to this day. Another species in the genus, *Cannabis indica* Lam. was formally 20 25

named somewhat later (de Lamarck, J B, 1785, ENCYCLOPEDIE METHODIQUE DE BOTANIQUE, 1(2):694-695), but is still very old in botanical history. In 1785, Jean-Baptiste Lamarck published a description of a second species of *Cannabis*, which he named *Cannabis indica*. Lamarck based his description of the newly named species on plant specimens collected in India. *C. indica* was described as relatively short, conical, and densely branched, whereas *C. sativa* was described as tall and laxly branched (Schultes R. E. et al, 1974, Harvard University Botanical Museum Leaflets, 23:337-367). *C. indica* plants were also described as having short, broad leaflets whereas those of *C. sativa* were characterized as relatively long and narrow (Anderson L. C., 1980, Harvard University Botanical Museum Leaflets, 28:61-69). *C. indica* plants conforming to Schultes' and Anderson's descriptions may have originated from the Hindu Kush mountain range. Because of the often harsh and variable (extremely cold winters, and warm summers) climate of those parts, *C. indica* is well-suited for cultivation in temperate climates.

Three other species names were proposed in the 1800s to distinguish plants with presumably different characteristics (*C. macroisperma* Stokes, *C. chinensis* Delile, *C. gigantean* Vilmorin), none of which are accepted today, although the epithet "indica" lives on as a subspecies of *C. sativa* (*C. sativa* ssp. *indica* Lam., Small and Cronquist 1976 Supra).

In the 20th century, two new names were added to the liturgy of proposed *Cannabis* species: *C. ruderalis* Janischewsky and a hybrid, x *C. intersita* Soják. (Small, E, Jui, P Y, and Lefkovich, L P, 1976, SYSTEMATIC BOTANY 1(1):67-84; Small and Cronquist 1976 Supra). Further, numerous names have been proposed for horticultural variants of *Cannabis* but as of 1976, "very few of these have been validly published as formal taxa under the International Code of Botanical Nomenclature" (Small and Cronquist 1976 Supra). Moreover, other recent work continues to focus on higher-order evolutionary relationships of the genus. *Cannabis* has been variously ascribed as belonging to mulberry family (Moraceae) (Engler, H G A, Ulmaceae, Moraceae and Urticaceae, pages 59-118 in: A. Engler and K. Prantl eds., 1889, DIE NATURLICHEN PFLANZENFAMILIEN 3(1). W. Engelmann, Leipzig, Germany; Judd, W S, Sanders, R W, and Donoghue, M J, 1994, HARVARD PAPERS IN BOTANY 5:1-51; Humphries, C J and Blackmore, S, A review of the classification of the Moraceae, pages 267-277 In: Crane and Blackmore 1989 id.); nettle family (Urticaceae) (Berg, C C, Systematics and phylogeny of the Urticales, pages 193-220, in: P. R. Crane and S. Blackmore eds., 1989, EVOLUTION, SYSTEMATIC, AND FOSSIL HISTORY OF THE HAMAMELIDAE, VOL. 2, HIGHER HAMAMELIDAE, Clarendon Press, Oxford, U.K.); and most recently in its own family with hops (*Humulus*), Cannabaceae, or hemp family (Systsma, K J, et al, 2002, AMERICAN JOURNAL OF BOTANY 89(9): 1531-1546). While the work of Small and Cronquist 1976 Supra, seemed to effectively confine the genus to a single species with 2 subspecies (*C. sativa* s., *C. s. indica*), each with two varieties (*C. s. s. var. sativa*, *C. s. s. var. spontanea*; *C. s. i. var. indica*, *C. s. i. var. kafiristanica*) largely on the basis of chemotaxonomy and interfertility of all forms, more recent work (Systsma et al. 2002 Supra), proposes a two-species concept, resurrecting the binomial *C. indica* Lam. Since Systsma et al. (2002) provides no key for discriminating between the species, the dichotomous key of Small and

Cronquist (1976), which accounts for all forms in nature, whether wild or domesticated, is preferred to classify the characteristics of the plants.

5 BRIEF SUMMARY OF THE INVENTION

The present invention relates to a new and distinct *Cannabis* cultivar designated 'AFZ'.

This invention relates to a new and distinctive *Cannabis* 10 cultivar designated as 'AFZ'. 'AFZ' cultivar that is a mix of *Cannabis* genetics from both northern and southern California. The mother plant A.F. (not patented) is a 3-way cross of Sour Diesel, Cindy 99, and the infamous Animal cut of Girl Scout Cookies. The father is the proprietary f1 breeder 15 stud Zuchi (Pending U.S. Plant patent application Ser. No. 17/950,084). (Applicant is not aware that either of the parent plants is patented in the United States or is the subject of a pending patent application in the United States.) A single plant was selected from a population of 250 seedlings. The 20 plants were grown and flowered indoors, in a tightly controlled environment, under mixed spectrum light conditions in order to see maximum genetic expression. AFZ is asexually produced in Orange County CA via stem cuttings and cloning method by the inventor. Asexual clones have been tested indoors and in greenhouses and the properties are found to be transmissible by such asexual reproduction.

The objective of 'AFZ's' creation was to unlock and identify new and unique smell and flavor profiles resulting from the enhanced terpene and flavonoid content.

30 Consumer demand continues to require new terpene and flavor profiles be brought to market, and in tandem, commercial operators need genetics that maximize wholesale cost while increasing profitability in the form of lower 35 production costs, and increased harvest size. It is understood that it is not the cannabinoids themselves that drive and direct the effects of *Cannabis* but it is the other phytochemicals, specifically terpenes, flavonoids, esters and aldehydes 40 that are responsible for the drastic difference in the perceived effects. Higher levels of Limonene are associated with an uplifting and euphoric effect, while myrcene is associated with effects that are described as calming and sleep inducing.

The inventor continues to actively create cultivars that 45 suit their own needs and the needs of their clients. The particular cultivar described was discovered in an area where the inventors are intentionally cross-pollinating various cultivars using standard Mendelian breeding procedures well known to those of ordinary skill. This resulted in the 50 seed stock from which the 'AFZ' plant was identified.

The inventor reproduces progenies asexually using stem cutting and cloning, as well as both nodal and meristem tissue culture. The plant continues to be asexually propagated at the inventor's greenhouses in Fallbrook, Calif.

55 The following are the most distinguishing and desirable chemical and physical characteristics when grown under normal conditions indoors under standard HID lighting. Chemical analysis was performed by the standard separation and isolation technique that is well known to those skilled in the art of analytical chemistry.

60 The resulting hybrid females produce large purple, green and blue streaked flower clusters that appear almost frosted white due to an immense amount of glandular trichomes that cover every cubic inch of the flower. These trichomes are rich in many different cannabinoids and terpenes that make this cultivar highly valuable for medicinal and recreational

cultivation. This hybrid is very easy to grow and a hardy plant that is resistant to most bugs and powdery mildew while able to yield 540-750 grams/m² in a sea-of-green or dense canopy style grow. A Sea of Green is way to describe growing many plants together to form a continuous canopy. As opposed to growing individual large plants to fill a space, this method groups smaller plants tightly together while maintaining a uniform appearance. AFZ expresses a very unique and distinct rippled and serrated leaf and trapezoidal flower structure and pattern unlike any of the parent plants or siblings. The trichome heads are larger and more tightly clustered as well. The selected plants express a shorter internodal length that allows for more flower sites within the same area, resulting in a larger overall yield of flower or resin. The fragrance is that of fresh baked apple pie, diesel fuel, lemon pepper and rubber cement. This unique combination of terpenes as described distinguishes AFZ from other related varieties in its odor, flavor, and resulting medicinal or recreational effects, including distinguishing from the parents and related known cultivars, such as 'TZA' (Ser. No. 17/950,089) and 'ZLT' (Ser. No. 17/950,091). Terpene comparison below:

AFZ is asexually propagated via removal of terminal colas from a mother plant. These cuttings are between 4-5" in length and are then inserted into rockwool cubes that are saturated with ph adjusted water with fertilizer. The plants are arranged in trays and covered with a clear dome to increase humidity and reduce light levels. The plants will sit covered for 5 days with a fresh air exchange every day under 24 hours of light. Starting on day 6 the plants will begin to

root and require watering in the trays and the domes will be vented until the humidity matches that of the external environment. By day 10-12, the plants will be ready for transplant and will be inserted into 6x6x6" rockwool cubes that are conditioned at 5.8 ph and 2.7ec. They will be moved into an area with 18 hours of light for 17-21 days until the root zone has fully developed. After the roots are seen to exit the bottom of the rockwool cubes, the plants will be moved into a room with only 12 hours of light to induce flowering. 10 These plants will grow under 12 hours of light for 60-65 days and are then ready for harvest.

To harvest, the entire plant is cut at the base and then weighed and logged. The whole plant is then dried under controlled conditions that are cold and dark for 14-21 days 15 before being carefully manicured and then allowed to rest for a further 14 days before final analysis.

Under careful analysis, asexually propagated AFZ's unique flavor and terpene profile, yield, and color is stable and reproducible both indoors and in greenhouse, and while 20 using different light fixtures and or nutrient blends.

3 grams of dried and manicured flowers were obtained from 1 of the claimed 'AFZ' plants.

The below cannabinoid and terpene results were obtained by high-performance liquid and gas chromatography, otherwise known as HPLC and GCMS. The standard analytical methods for these procedures were utilized to obtain the following results.

The selected dried and manicured flowers were submitted to Agriscience Laboratories for analysis.

50 BRIEF DESCRIPTION OF THE DRAWING

Total Cannabinoids: 30.8 @ 9.4% Moisture Content

FIG. 1 is a view of the 'AFZ' plant in bloom.

FIG. 2 is a close-up view of an 'AFZ' flower cluster.

55 FIG. 3 is a close-up view of a manicured 'AFZ' flower cluster.

DETAILED BOTANICAL DESCRIPTION

60 'AFZ' has not been observed under all possible environmental conditions, and the phenotype may vary significantly with variations in environment. The following observations, measurements, and comparisons describe this plant as grown at Mentone, Calif., when grown in the greenhouse, nursery or field, unless otherwise noted. The new plant reproduces true to type with all of the characteristics, as

herein described, firmly fixed and retained through successive generations of such asexual propagation. The claimed plant expresses a very unique and distinct rippled and serrated leaf and trapezoidal flower structure and pattern unlike any of the parent plants. The trichome heads are larger and more tightly clustered as well. The selected plants express a shorter internodal length that allows for more flower sites within the same area, resulting in a larger overall yield of flower or resin.

The color chart referenced is standard hexadecimal Web Pantone Color Chart well known to those of ordinary skill in Internet web site design.

The Plant

Type (life form and habit). Herbaceous tap-rooted annual.

Seeds: The seeds are round/oval in shape with large zigzag striped patterns that cover the length of the seed. They are greyish brown PMS 462 with strong marbling and they can weigh between 0.1-0.2 g each.

Inflorescence: The flowers are bulbous at the base and emerge outward into sharp points. The % of male vs female plants was approximately 65% female and 35% males in the selection process. There was <3% hermaphrodite expression from seed and after taking clones, the hermaphroditic expression was not seen again. The flowers are arranged in a spiral pattern up the stem similar to Brussels sprouts with each flower being fully formed and not contributing to a homogeneous "cola" shape. The flowers turn a dark shade of purple PMS 262 C at harvest with the stem staying very light vibrant green PMS 364. The fragrance is that of fresh baked apple pie, diesel fuel, lemon pepper and rubber cement.

Leaves: The fan leaves are large and stout. They can be 8-12" long and have a total width of 8-10" with some overlap between every leaflets. The trichomes are mostly capitate stalked and are wet but sandy gritty to the touch, releasing a heavy aroma of baked apple pie, diesel fuel, lemon pepper and rubber cement. Leaflet shape is a long oval with ripples on all sides, they do not lie flat. An average number of leaflets is between 7-11 depending on the total plant size and health. The top of the leaf is dark green PMS 349 with the bottom being light green PMS 360.

Petioles: Typically 2.2-4.5" long and 0.2-0.3" in diameter. The longer and older petioles will show anthocyanin production starting closer to the stem and moving out toward the leaf rachis. Trichomes are glandular with capitate stalked visible and bulbous trichomes and capitate-sessile all around. Petioles are dark green PMS 364.

Stems: The stem shape is a large oval that has a zigzag pattern as it grows. Each node will begin to grow in the opposite direction of the previous node at the same angle of

growth. The stem is round and can reach a diameter of 1.25-2" when grown with a shallow groove depth and thick pith presence (full stems). There are no visible trichomes growing on the stem. Stem color is green PMS 364.

5 Bract: The bract is 0.14" in diameter and 0.244" in length with 2 stigmas emerging from the center. They are absolutely covered with capitate-stalked trichomes and also house bulbous and capitate-sessile trichomes throughout. Light green color PMS 361.

10 Bracteole: Usually between 0.11-0.125" in length. They are slender spear-shaped and light green PMS 360.

Height: The average height can be modified depending on the volume of growing media and the irrigation frequency. In a 6x6x6 rockwool cube, being fed 1500-2000 ml per day 15 a plant will average around 77-82" in height. The selected plant is grown in clusters with 9 plants per 16-24 ft². An incredibly vigorous plant, clones will take between 6-9 days to show roots and will reach a height of 24-28" after only 17-21 days.

20 Stipules: Found at each node and are usually between 0.2-0.25" in length. They are spear-shaped and accompanied by white pistils regardless of the light cycle or season and are light green PMS 361.

Classification. Cultivars of *Cannabis sativa*.

25 This cultivated line possesses intoxicating properties, and so the Subspecies *sativa* and its varieties (var. *sativa* and *spontanea*) are eliminated from consideration.

Growth conditions: The plants are grown and are meant to be grown in a tightly controlled environment. They have 30 been able to withstand temperatures above 105 degrees F. with 95% RH.

Market use: The market use for this product is medical and recreational *Cannabis* flower as well as extracts and infused goods. Individual plants grown with the above 35 methods yield an average of 3000 g at harvest resulting in a dry flower weight of 150-200 grams.

All references cited in this specification, including but not limited to patent publications and non-patent literature, and references cited therein, are hereby incorporated by reference. 40 The discussion of the references herein is intended merely to summarize the assertions made by the authors and no admission is made that any reference constitutes prior art. Applicants reserve the right to challenge the accuracy and pertinence of the cited references.

45 What is claimed is:

1. A new and distinct variety of *Cannabis* plant named 'AFZ', substantially as illustrated and described herein.
